US0D1001454S

(12) **United States Design Patent** (10) **Patent No.:** **US D1,001,454 S**
(45) **Date of Patent:** **** Oct. 17, 2023**

(54) **INSOLE**

(71) Applicant: **David Epstein**, Pleasant Ridge, MI (US)

(72) Inventor: **David Epstein**, Pleasant Ridge, MI (US)

(**) Term: **15 Years**

(21) Appl. No.: **29/774,121**

(22) Filed: **Mar. 15, 2021**

(51) LOC (14) Cl. **02-04**

(52) U.S. Cl. **USPC .....** **D2/961**

(58) **Field of Classification Search**

(57) **CLAIM**

The ornamental design for an insole, as shown and described.

DESCRIPTION

FIG. 1 is a first perspective view of an insole according to a first embodiment;

FIG. 2 is a second perspective view from the other side of the insole of FIG. 1;

FIG. 3 is a top view of the insole of FIG. 1;

FIG. 4 is a bottom view of the insole of FIG. 1;

FIG. 5 is a right side view of the insole of FIG. 1;

FIG. 6 is a left side view of the insole of FIG. 1;

FIG. 7 is a front view of the insole of FIG. 1;

FIG. 8 is a rear view of the insole of FIG. 1;

FIG. 9 is a first perspective view of an insole according to a second embodiment;

FIG. 10 is a second perspective view from the other side of the insole of FIG. 9;

FIG. 11 is a top view of the insole of FIG. 9;

FIG. 12 is a bottom view of the insole of FIG. 9;

FIG. 13 is a right side view of the insole of FIG. 9;

FIG. 14 is a left side view of the insole of FIG. 9;

FIG. 15 is a front view of the insole of FIG. 9; and,

FIG. 16 is a rear view of the insole of FIG. 9.

The broken lines shown in the drawings are included for the purpose of illustrating environmental structure and form no part of the claimed design.

1 Claim, 14 Drawing Sheets
